UNITED STATES PATENT OFFICE.

WILLIAM W. CROOKER, OF LYNN, MASSACHUSETTS, ASSIGNOR TO THE WM. W. CROOKER MANUFACTURING COMPANY, OF SAME PLACE.

DEVICE FOR INKING THE EDGES OF BOOT OR SHOE SOLES.

SPECIFICATION forming part of Letters Patent No. 367,895, dated August 9, 1887.

Application filed December 4, 1886. Serial No. 220,653. (No model.)

To all whom it may concern:

Be it known that I, WILLIAM W. CROOKER, of Lynn, in the county of Essex and State of Massachusetts, have invented certain new and useful Improvements in Devices for Inking the Edges of Boot or Shoe Soles, of which the following is a specification.

My invention relates to devices for "inking" or coloring the edges of boot and shoe soles preparatory to burnishing or polishing the same.

It is the object of my invention to produce a device of the character mentioned which shall be simple in construction, convenient and effective in use, and in which the supply of ink or coloring-liquid to the brush can be regulated with the utmost nicety.

My invention consists in a construction whereby the ink-distributing brush is arranged on the end of the reservoir-handle in a position oblique or at an angle to the direction of its length, which construction affords great convenience in the manipulation of the device.

My invention also consists in a construction whereby the guard for preventing the coloring-liquid from reaching the upper of the boot or shoe is yieldingly connected with the device for the purpose of rendering the operation of the same at certain points more effective.

My invention also consists in improved means for attaching the brush to the device.

My invention also consists in improved means for regulating the flow of the ink or coloring-liquid to the brush.

Reference is to be had to the accompanying drawings, and to the letters of reference marked thereon, which form a part of this specification, in which drawings the same letters of reference indicate the same parts wherever they occur.

In the drawings, Figure 1 represents a side elevation of my invention. Fig. 2 represents a top plan view, parts being shown as broken away. Fig. 3 represents a vertical longitudinal section of the invention, the means whereby a flexible tube may be attached to the reservoir-handle being shown in elevation. Fig.

4 represents a section on the line *xx*, Fig. 1. 50 Fig. 5 represents an end view of the invention.

In carrying out my improvements I provide a tube, *a*, of brass or other suitable material, and cut a screw-thread in the bore at one end, 55 turning therein a hollow exteriorly-screw-threaded plug, *b*, which affords means for attaching a flexible tube, *c*, with the device, which flexible tube may be connected with a fountain of any suitable character affording 60 a supply of ink or coloring-liquid for use in the device. The opposite end of the handle is cut away on a plane at an angle or obliquely to the direction of its length and a dovetail groove formed therein, and a dovetail projection, *d*, constructed on the back of the distributing-brush *e*, of a form adapted to fit closely in said dovetail groove, which affords a convenient and effective means of attaching the brush to the reservoir-handle *a*, and at the 70 same time gives the brush such position as to present its full face to the sole when the device is held in the most natural and convenient position in the hand of the operator.

In the handle above the dovetail groove 75 formed therein, and substantially in line therewith, I tap a screw-threaded hole, *f*, and insert therein a screw, *g*, which, by preference, does not extend entirely through the handle *a*. I then drill holes *h* through the back or dovetail portion of the brush and the screw *g* to the interior or reservoir *i* of the handle, and by this means provide for the flow of ink from the reservoir *i* to the brush *e*, and by slightly turning the screw, which may be done by the 85 aid of an ordinary screw-driver, I may shut off the flow of ink entirely, or admit a more or less bountiful supply to the brush, as circumstances or the nature of the work may require, regulating this matter with the greatest nicety.

The sides of the reservoir-handle at its forward end are flattened by cutting away a portion of the material, as represented at *j*, and to one of these flattened sides is pivoted, as at 95 *k*, the guard *l*, projecting downward along the side of the brush *e*, so as to enter the crease between the upper and sole of the boot or shoe

being operated upon, and prevent the brush from applying the ink or coloring-liquid to the upper.

The guard *l* is provided toward its forward end with a short slot, *m*, extending through which and into the handle *a* is a screw, *n*, whereby the movement of the guard *l* on its pivot *k* is limited. A spring, *o*, coiled about a stud, *p*, and having one end secured under a pin, *q*, is arranged to have its free end rest on the guard *l*, and thus hold the guard down with a yielding pressure, so that in using the device in inking or coloring short curves or angles in the edge of the sole, and to meet other exigencies, the guard will yield slightly and permit the distributing-brush to be further depressed than could be done were this provision not made.

The operation and manner of using my device will now be understood without further description.

While I have described what I regard as the best manner of constructing the various parts, it is obvious that their form and arrangement may be varied without departing from the nature or spirit of the invention.

Having thus described my invention, what I claim is—

1. A reservoir-handle consisting of a hollow tube having one end cut away on a plane oblique or at an angle to the direction of its length, and an ink or color distributing brush secured to said angular end, combined and operating substantially as and for the purposes hereinbefore set forth.
2. A reservoir-handle, an ink-distributing brush secured on one end thereof, and a guard for preventing the coloring-liquid from reaching the upper of the boot or shoe, said guard being yieldingly connected with the reservoir-handle, all arranged, combined, and operating substantially as and for the purposes hereinbefore set forth.

3. A reservoir-handle consisting of a hollow tube having one end cut away on a plane oblique or at an angle to the direction of its length, a dovetail groove formed in said angular portion, and a distributing-brush having a dovetail projection on its back adapted to fit snugly in said groove, whereby the brush may be attached to the handle, all combined and arranged substantially as and for the purposes hereinbefore set forth.

4. A reservoir-handle consisting of a hollow tube having one end cut away on a plane oblique or at an angle to the direction of its length, a distributing-brush secured to said angular portion, a screw-threaded hole formed in the handle above the brush, and holes formed in the back of the brush and through the screw, whereby the ink or coloring-liquid in the reservoir-handle may be supplied to the brush, and the flow of said ink or liquid regulated, all combined, constructed, and arranged substantially as and for the purposes hereinbefore set forth.

5. In a device for inking the edges of boot or shoe soles, an ink-distributing brush, a guard, *l*, adapted to enter the crease between the sole and upper of the boot or shoe, and located alongside of the brush to prevent the ink from being distributed on the upper, and a support for said guide, the latter having a yielding connection edgewise with its support, all constructed, combined, and operating substantially as and for the purposes hereinbefore set forth.

In testimony whereof I have signed my name to this specification, in the presence of two subscribing witnesses, this 1st day of December, 1886.

WILLIAM W. CROOKER.
